UNITED STATES PATENT OFFICE.

BAKER M. TOMBERLIN, OF SANTA ROSA, CALIFORNIA.

COLLAPSIBLE CRATE.

1,231,459.

Specification of Letters Patent. Patented June 26, 1917.

Application filed March 12, 1913. Serial No. 753,748.

To all whom it may concern:

Know all men that I, BAKER M. TOMBERLIN, a resident of the city of Santa Rosa, county of Sonoma, State of California, 5 United States, and residing at Number 309 D street, in said city, am the original inventor in the Improvement of Collapsible Crates.

This invention relates to improvements in 10 the art of containers, and more particularly to such as are adapted for occupying a minimum amount of space while not in use, and to this end the object of the invention is the provision of a crate or container of 15 maximum capacity when unfolded or expanded and occupying a minimum space when collapsed or folded.

A further object of the invention is the 20 locating of certain locking elements and the proportioning of the parts thereof relative to the proportions of parts of the crate structure for enabling the locking elements to lock all of the parts of the crate structure in both the collapsed and unfolded positions.

25 With these and further objects in view, as will in part hereinafter become apparent and in part be stated, the invention comprises certain novel constructions, combinations and arrangements of parts as subsequently specified and claimed.

In the accompanying drawings,—

Figure 1 is a view in side elevation of a structure embodying the features of the present invention.

35 Fig. 2 is a transverse, vertical section taken on the plane indicated by line 2—2 of Fig. 1.

Fig. 3 is a top plan view of the parts shown in their collapsed position.

40 Fig. 4 is a fragmentary, vertical section illustrating one of the locking devices and its engaging parts with the parts unfolded.

Fig. 5 is a fragmentary detail horizontal section taken on the plane indicated by line 5—5 of Fig. 1.

45 Fig. 6 is a similar section taken on the plane indicated by line 6—6 of Fig. 1.

Fig. 7 is a view similar to Fig. 4 with the parts illustrated as collapsed.

Figs. 8 and 9 are detail, horizontal sections taken respectively on the planes indicated by lines 8—8 and 9—9, of Fig. 1.

Referring to the drawings by numerals, 1, 1 indicate the side plates, 2, 2 the end

plates, and 3, 3 the top and bottom plates of a collapsible crate embodying the features 55 of the present invention. The side plates are each bound by a marginal stiffening rod 4 inclosed along the upper and lower edges of the respective plate by marginal rolls, the side and end plates being formed with 60 interlacing eyes, 5, 5 and 6, 6, connected by the rod 4, serving as a pintel so that the sides and ends are hinged together. Each of the plates 3 has its edges bound by a marginal stiffening rod 8 inclosed in a 65 marginal roll formed of the material of the edge portions of the respective plate 3, and the upper plate 3 is engaged by straps or leaves 9, 9, forming hinges, each being formed with an eye inclosing the adjacent 70 portion of the marginal rod of the rear side plate 1, the bottom 3 being likewise provided with similar hinge leaves 9 each having an eye engaging the lower portion of the marginal rod of the front plate 1, so that 75 when the plates 3 are released and capable of free swinging movement the upper plate 3 is adapted to be swung to a vertical pendant position, as indicated in dotted lines in Fig. 2, and the lower plate 3 is adapted to be 80 swung to a vertical upstanding position, as indicated in dotted lines in said figure. The upstanding portion of the bottom 3 is also indicated by the dot and dash line in Fig. 1, from which its relative proportions with respect to the location of the coöperating parts 85 of the locking elements, as will be herein-after specified, are made apparent.

The interior of the crate may be divided in any of numerous ways, and one desirable 90 means of division is indicated consisting of the provision of inwardly extending vertical sleeves 10, 10. A partition plate 11 is disposed within the crate or container and is bound by a marginal rod 12 inclosed substantially throughout the edges of the plate 11 by marginal rolls formed of the edge portions of the plate, the plate being formed with notches 13, 13, at appropriate points for accommodating the sleeves 10, 100 and the rod 12 being disposed to extend through the several brackets so as to form a loose hinge connection between the partition 11 and the side plates 1. Thus the partition is free to slide laterally for a limited 105 distance, controlled by the amount of space

inclosed by the several sleeves 10, and at the same time the partition 11 is free to swing laterally in either direction as the parts of the crate are being collapsed into the position indicated in Fig. 3 during relative pivotal movement of the eyes 5 and 6.

It is to be noted that the invention is essentially adapted for use of metallic sheets or sheets of other suitable material, the 10 showing in the drawing being obviously disproportionate as to the thickness of the sheets in order to enable effective disclosure of the structure of the parts, the actual metal sheets being of course, so thin as to be difficult to illustrate in cross section.

15 A pair of locking elements is preferably provided for each plate 1 and disposed to engage the respective plate 3 when the parts are expanded or unfolded and to engage the 20 edges of both side plates and lock all parts together when collapsed. While I have referred to and illustrated a pair of such locks for each plate 1 and this number is preferred, it is obvious that a single lock may 25 be employed or a greater number than two utilized when desired, and since each of the locks is an exact duplicate of all the others, one only will be described, and the description and reference numerals will apply 30 equally to all.

Fixed to the respective plate 1 at the inner face thereof is a spring hook 14 having its free end extended outwardly through an aperture 15 formed in the plate 1, and 35 the said hook is adapted to interlock with an inwardly turned hook 16 extending from the free end of a slide or bolt 17, the said bolt being slidably mounted, sustained and guided by a bracket 18 40 fixed to the bolt 17 and extending transversely thereof and having terminal portions lying within the respective plate 2, the bolt being arranged on the outside thereof and the bracket 18 being accommodated by a vertical slot 19 formed in the respective plate. 45 The upper end of bolt or slide 17 or end opposite that provided with hook 16 terminates in an eye 20 extending between a pair of eyes 21 formed by the bifurcation of a 50 hook member 22, the hook of which is disposed and proportioned to extend beyond and across the adjacent edge portions of the respective plates 1 and 3 and into an aperture 23 in the respective plate 3 for locking 55 the parts together in their unfolded position, the said hook being also dimensioned to inclose the marginal portions of both of the side plates and the engaged portion of the respective plate 3 when the parts are collapsed, as indicated in Fig. 7. The slide or 60 bolt 17 is of a length proportioned and location selected for causing the aperture 23 of the respective plate 3, when disposed in its vertical position, to register with the corresponding aperture 15 and thus enable the

hook 16 to overlie and engage the respective portion of the given plate 3 when the parts are collapsed as indicated in Fig. 7.

In operation, the parts being in the position indicated in Figs. 1 and 4, if it is desired to gain access to the crate it is only necessary to grasp the lower end of the two slides or bolts 17 and pull them outwardly until the hooks 16 and 14 are disengaged, and then to slide the bolts 17 upwardly until the hooks 22 leave their engagement with apertures 23 and then to swing the hooks 22 outwardly, as indicated in dotted lines in Fig. 4. The top plate 3 can then be swung upon its hinges 9 to its vertical pendent position and access freely had to the interior of the crate. To close the crate again it is only necessary to swing the plate 3 back to its closed position and then press the slides or bolts 17 manually downwardly until the hooks 16 and 14 reengage, and thereupon the parts are in their closed and lowered position. It is to be noted that the downward movement of the slides 17 is made easy by the riding of the curved portion of hook 16 over the corresponding portion of hook 14, it being observed, of course, that the engagement and release of the hooks 16 and 14 is accomplished by the springing of the material of bolts or slides 17. When 95 it is desired to collapse or fold the crate the top plate is swung to its vertical pendent position and the bottom plate is swung to its vertical upstanding position by an identical operation, inversely applied, 100 as that just described, and then the sides 1 are given a diagonal collapsing movement until they approach each other as nearly as possible with the partition 11 intervening, whereupon the parts will be substantially in 105 the position indicated in Fig. 3. Care is exercised to see that the plates 3 are located as near the sides 1 as possible with the apertures 23 registering with apertures 15, and then the sides 7 are slid back to establish 110 locking position, whereupon the hooks 16 of the slides will spring over the upper headed edges of the plates 3 and again engage the hooks 14 so that the plates 3 are effectively 115 locked in position. The particular hooks 22 which are disposed substantially centrally of the collapsed mass are at the same time brought over the contiguous edges of the parts to the position indicated in Fig. 7, and the said edges are thus effectively locked 120 against separation so that the collapsed condition is maintained until it is desired to restore the unfolded or expanded position, when it is necessary to spring the hooks 16 outwardly and move the same upwardly for enabling release of the parts which are restored to their unfolded position by a reverse movement to that last described.

What I claim is:—

1. The combination with a container hav-

- ing side, end, top and bottom walls hinged together, the top wall being free to swing upon its hinge, of a plate slidably engaging one of the side walls and having a hook at its upper end adapted to engage the top wall and having a hook at its lower end, and a spring hook fixed to the side wall adjacent to and adapted to interlock with the hook of the lower end of the sliding plate.
2. The combination with a container having side, end, top and bottom walls hinged together, the top wall being free to swing upon its hinge, of a plate slidably engaging one of the side walls and having a hook at its upper end adapted to engage the top wall, and having a hook at its lower end, the side wall being formed with an aperture in which the last named hook is adapted to extend, and a spring hook fixed to the inside of said side wall and disposed to extend into the aperture for interlocking with the hook at the lower end of the sliding plate.
3. The combination with a container having side, end, top and bottom walls hinged together, the top wall being free to swing upon its hinge, of a plate slidably engaging one of the side walls, the side wall thus engaged being formed with a vertical slot, a retaining plate fixed to the sliding plate and extending through the slot and lapping the inner face of the side wall, said sliding plate having hooks at its ends, one adapted to engage and lock the top wall from swinging, and a spring hook carried by the sliding plate and disposed to engage the other hook of the sliding plate.
4. In a folding crate, the combination of a collapsible structure having side plates, hinged top and bottom plates, the top plate being hinged at the opposite side of the structure from the bottom plate, and locking means carried by each of the side plates proportioned for engaging and locking the top and bottom plates in position with the structure unfolded, the top and bottom plates being dimensioned and located for swinging on their hinged connections to a folded position contiguous to the respective locking elements, the said locking elements being adapted to engage and lock the top and bottom plates in their folded positions.
5. In a folding crate, the combination with a collapsible structure comprising side and end plates hinged together, a top plate hinged to the upper edge of one of the side plates, a bottom plate hinged to the lower edge of the other side plate, each of the top and bottom plates being hinged to swing from a horizontal to a vertical position, and locking means fixed to the last mentioned side plate adjacent its upper edge and similar locking means fixed to the other side plate adjacent its lower edge, each of the top and bottom plates being proportioned for extending, when in their vertical posi-

tions, to the locking means of the respective side plate to which the top or bottom plate is hinged, and the locking means being adapted to lock the last mentioned plates in both their vertical and horizontal positions.

6. In a folding crate, the combination of side and end plates hinged together, a top plate hinged to one of the side plates and adapted, when in its unfolded position, to engage the other side plate and the end plates for retaining the same against collapse, a similarly disposed bottom plate hinged to the other side plate, the hinges of the top and bottom plates being constructed to enable said plates to be swung from a position engaging the side and end plates to a vertical position for enabling collapse of the side and end plates with respect to each other, and a shiftable lock carried by each of the side plates adapted to be shifted to and from a position locking the top and bottom plates in their unfolded position for locking the same in their folded position.

7. In a folding crate, the combination of side and end plates hinged together, a top plate hinged to one of the side plates and adapted, when in its unfolded position, to engage the other side plate and the end plates for retaining the same against collapse, a similarly disposed bottom plate hinged to the other side plate, the hinges of the top and bottom plates being constructed to enable said plates to be swung from a position engaging the side and end plates to a vertical position for enabling collapse of the side and end plates with respect to each other, and a shiftable lock carried by each of the side plates, adapted to be shifted to and from a position locking the top and bottom plates in their unfolded position for locking the same in their folded position, each of said shiftable locks having means adapted to engage and lock the collapsed parts in their collapsed condition.

8. In a folding crate, the combination of a collapsible container, slidably mounted bolts fixedly carried thereby, and hooks on the ends of the bolts adapted to engage and lock the parts respectively in their folded and unfolded conditions.

9. In a folding crate, the combination of a collapsible container having side plates and top and bottom plates, one of the latter plates being hinged to each of the former, and the hinged connection being such as to enable such top and bottom plates to swing from a horizontal or open position to a vertical or closed position, each of the top and bottom plates being formed with a lock receiving aperture, a lock carried by one of the side plates and having a hook adapted to engage the aperture of the plate hinged to the other side plate, and a similar lock carried by the last mentioned side plate, and having a hook adapted to engage the

4
notch of the plate hinged to the first side plate, each of said locks having a hook disposed to engage the aperture of the respective top or bottom plate hinged to its engaged side plate, when the top and bottom plates are disposed in their vertical positions.

10. In a folding crate, the combination of hinged side and end plates, a top plate hinged to one of the side plates, and adapted to swing from an open horizontal position to a collapsed vertical position, a similar bottom plate hinged to the other side plate, a sliding bolt carried by each side plate and having a hook at its outer end and a hook at its inner end, the hook at the outer end being adapted to engage and retain the respective top or bottom plate when the latter is in its open position, and the hook at the inner end adapted to engage and retain the relatively opposite top or bottom plate when the latter plates are in their folded positions, the outer hooks of the locking bolts in the last named instance, being adapted to engage and lock the side plates in a collapsed position.

11. In a folding crate, the combination of a collapsible container, slidably mounted

bolts carried thereby, and hooks hinged on the ends of the bolts and adapted to engage and lock the parts respectively in their folded and unfolded conditions.

12. In a folding crate, the combination of side and end plates hinged together, a bottom plate hinged to one of the sides and adapted to swing from a horizontal unfolded position to a vertical folded position, a top plate similarly constructed and hinged to the other side plate, a sliding locking bolt engaging the upper portion of the side plate to which the bottom plate is hinged, a similar locking bolt slidably carried by the other portion of the other side plate, each locking bolt being formed at its outer end with a hook adapted to engage the respective top or bottom plate in its unfolded position, and each locking bolt being provided with an inner end portion adapted to engage and lock the respective top or bottom plate in its folded position.

Dated, San Francisco, California, March 5th, 1913.
